UNITED STATES PATENT OFFICE.

ARTHUR R. KRAUSE, OF WOODHAVEN, NEW YORK, ASSIGNOR TO LION ELECTRIC MANUFACTURING CO., INC., A CORPORATION OF NEW YORK.

DESIGN FOR A BACKPLATE FOR LIGHTING FIXTURES.

Application filed February 28, 1925. Serial No. 12,526. Term of patent 7 years.

To all whom it may concern:

Be it known that I, ARTHUR R. KRAUSE, a citizen of the United States, and a resident of Woodhaven, county of Queens, and State of New York, have invented a new, original, and ornamental Design for Backplates for Lighting Fixtures, of which the following is a specification, reference being had to the accompanying drawing, forming a part thereof.

In these drawings:

Fig. 1 is a front elevational view of the backplate for lighting fixtures, and

Fig. 2 is a diagrammatic outline in the side elevation of the backplate for lighting fixtures.

I claim:

The ornamental design for a backplate for lighting fixtures, substantially as shown.

ARTHUR R. KRAUSE.
